SUPPORT FOR AWNINGS OR SUNSHADES

Arthur Joseph Pope, New York, N. Y.

Application March 14, 1935, Serial No. 11,053

20 Claims. (Cl. 135—5)

The present invention relates to supports for awnings or sunshades and is more particularly directed toward the provision of supports for awnings and sunshades of a type adapted to be used on the lawn or beach and to be bodily movable and adjustable as desired.

The present invention contemplates a structure for these purposes wherein the fabric forming cover is supported on a rigid substantial frame mounted on a horizontal axis a suitable distance above the ground and provided with means to tilt it about this horizontal axis so as to control the direction of drainage and of the shadow. According to the present invention the tiltable frame and the parts associated with it are so constructed that the adjustment may be readily effected and the parts securely held in adjusted position.

A further object of the present invention is to design the metal parts which support the covering material in such a way that they may be produced inexpensively, shipped unassembled and easily reassembled at the place of use. Other and further objects will appear as the description proceeds.

The accompanying drawings show, for purposes of illustrating the present invention, two of the many embodiments in which the invention may take form, it being understood that the drawings are illustrative of the invention rather than limiting the same. In these drawings:

Fig. 1 is a perspective view showing an awning support;

Fig. 2 is an end elevational view showing a portion of the assembly;

Fig. 3 is a vertical sectional view taken on the line 3—3 on Figure 2;

Fig. 4 is a fragmentary view showing a detailed view of construction;

Fig. 5 is an elevational view taken in the direction of the arrow 5 of Figure 1;

Fig. 6 is an elevational view taken in the direction of the arrow 6 of Figure 5;

Fig. 7 is an end elevational view illustrating a modified form of construction;

Fig. 8 is a side elevational view of the construction shown in Figure 7;

Fig. 9 is an enlarged sectional view on the line 9—9 of Figure 7;

Fig. 10 is an enlarged sectional view on the line 10—10 of Figure 8 omitting the ornamental brace; and

Fig. 11 is a fragmentary top plan view of the lower T.

The awning support shown herein is one particularly designed to support a portable awning

for use on lawns or at the seashore. As here shown it has vertical supporting members 10 and 11 which extend upwardly from horizontal bottom members 12 and 13 carrying T's 12' and 13', also rollers as indicated at 14. The upper ends 10a and 11a of the vertical members 10 and 11 are received in sockets 15 and 16 carried in T-shaped members 17 and 18. These T-shaped members are secured at the ends of a long rigid tube 19 preferably by welding or by making the 10 T's and tube out of a single steel casting.

Plugs 20 are welded in place in the ends of the tube 19. These plugs are drilled near the lower edge as indicated at 21 to receive a shaft 22. The ends of this shaft extend beyond the plugs 20 and 15 are reduced and preferably made square as indicated at 23.

Blocks 24 and 25 are provided with square holes to fit the square ends on the shaft 22 and are locked to it by lock screws indicated at 26. The 20 end members 24 and 25 are provided with transverse holes indicated at 27 to receive horizontal tubular members 28 and 29. These may be locked in place by screws indicated at 30. The members 28 and 29 are secured to long members 31 and 32 so as to provide a rectangular frame for the awning cover. This cover supporting frame forms a rigid structure connected to and supported by the shaft 22 and may be tilted about this shaft as an axis so as to be at 30 various angles to the horizontal. By rigidly securing the blocks to the shaft and the frame to the blocks, it is obvious that an extremely rigid framework is provided and one which will not twist out of shape even when excessive loads are 35 applied.

In order to secure the cover supporting frame in an adjusted position, suitable locking means are provided. This is here shown in the form of a pair of semi-circular arc-shaped members 33 40 and 34 loosely connected at their ends 33a and 33b to pins 35 carried by straps 36 and 37 secured to the tubular members 28 and 29. The members 33 and 34 are provided with holes indicated at 38 adapted to fit over posts 39 carried by the 45 uprights 10 and 11. The holes 38 are so placed that the frame may be tilted to a suitable angle and are preferably placed off center so that the frame cannot be locked in horizontal position. To hold the adjusting means in place suitable 50 keys 41 are provided.

In making an adjustment the key 41 is removed from one side and this allows the corresponding semi-circular member to hang vertically as indicated by dot lines of Figure 5. The 55

other key 41 is then pulled out of the post and one can tilt the frame about the axis of shaft 22 to adjust the angle at which the frame is to be locked. It can then lock into the desired 5 position and then the other semi-circular member moved to bring it into engagement with the other post 39 so that the key 41 can be inserted. With this method of operation it is obvious that 10 one person can easily adjust the frame and that it is not necessary to loosen the frame so that it can fall or shift out of position.

The parts 10, 11, 12, 13, 17, 18, 28, 29, 31 and 15 32 may, if desired, be made out of ordinary pipe fittings. To facilitate assembling and reduce the cost of construction, these parts are preferably 20 designed so as not to require cutting and threading of pipes. Tubular steel castings and unthreaded pieces of pipe may readily be employed for these parts. Where this is done the vertical 25 members 10 and 11 are secured to the T's 12, 13', 17 and 18 by pins indicated at 50, and the cross members 28 and 29 are secured to the longitudinal members 21 and 32 by employing elbows 51 welded to the longitudinal members and secured to the cross members by pins 52 as indicated in Figure 4.

The strap members 36 are preferably welded 30 at the proper point on the cross members 28 and 29 so that these members may be passed through the openings 27 in the end members 24 screws 39 inserted, and then the arc-shaped members 33 and 34 and straps 37 are secured in place by fixedly securing the straps 37 at the desired point. There is no possibility of the parts being off 35 center.

The cover indicated at C is secured to the 40 frame in any desired manner. Owing to the arrangement of parts, the cover may be held flat without any bulges or irregularities. The upper surfaces of the members 17 and 18, 24 and 25 are the same distance from the axis of the shaft 22 and hence the flatness of the cover is not disturbed when adjustments of the frame are made. By having the members 28 and 29 above the shaft 45 axis 22 as shown, it is possible to have these members and the surface of the tubular member 19 adjacent the cover in the same plane. These frames may be readily made strong enough to withstand severe usage without distorting them so as to render adjustments difficult or to impair the appearance.

In the arrangement shown in Figures 7 to 11 50 inclusive the awning support is made in the same general manner as that of Figures 1 to 6 and operates generally the same way.

The bases of the stand each comprise a horizontal cross member 51 similar to the members 12 and 13. The horizontal member is received in a special T-shaped casting 52, being welded in place as indicated at 53. The upper arm of 55 this T-shaped casting has a non-circular tapered opening 54 and a short socket 55. The vertical members are alike and one is indicated in the drawings at 56. These vertical members comprise a length of pipe 51 and two end members 58 and 59, each in the form of a casting having a squared tapered end as indicated. The vertical members 56 are inserted in place as indicated in Figure 7 and a clamping screw 59 securely fastens the parts together.

An angle member 60 similar to the pipe T 55 is provided with a tapered squared socket to receive the tapered upper end of the vertical member 58 of the member 56, these parts being secured together by a clamping screw 61. The

elbow member 60 is welded to a tube 62 which forms the upper horizontal tubular member and corresponds with the part 19 of Figures 1 to 5.

A shaft 63 is mounted in bearing holes 64 in the ends of the elbows 60. This shaft projects beyond the ends of the elbow member 60 and is secured as indicated at 65.

The cover supporting frame comprises transverse end members one of which is indicated at 66 and side members which are indicated at 67 10 and 68. These members are fastened together by elbow couplings 69 similar to those shown in Figure 4. The transverse members 66 of the cover supporting frame are provided with lugs 70 welded in place and these lugs have squared holes 15 to receive the squared ends of the shaft 63 so that the two transverse members tilt in unison.

Semi-circular straps 71 are welded to the pipes 66. The straps are received in open yokes 72 welded to the upright members. Each strap 71 20 has a series of openings 75 adapted to move past openings 76 and 77 in the yoke 72. A pin 78 passes through these aligned openings so as to secure the tilttable frame in adjusted position.

It is obvious that the invention may be embodied in many forms and constructions within the scope of the claims, and I wish it to be understood that the particular forms shown are but two of the many forms. Various modifications and changes being possible, I do not otherwise 30 limit myself in any way with respect thereto.

This application is filed as a continuation in 35 part of my co-pending application for patent for awnings or sunshades, Serial No. 753,583, filed November 19, 1934.

35

What is claimed is:

1. An awning support having a fixed horizontal tubular member, a revolvable shaft therein, an awning cover supporting frame carried by the ends of the shaft so that the frame may be tilted to various angles relative to the horizontal, and means to secure the frame in adjusted position.

2. An awning support having spaced vertical supports, a fixed horizontal tubular member connected to the upper ends of the supports, a revolvable shaft in the tubular member, an awning cover supporting frame carried by the ends of the shaft so that the frame may be tilted to various angles relative to the horizontal, and means connecting the frame and one of the vertical supports for securing the frame in adjusted positions.

3. An awning support having spaced vertical supports, a fixed horizontal tubular member connected to the upper ends of the supports, a revolvable shaft in the tubular member, an awning cover supporting frame carried by the ends of the shaft so that the frame may be tilted to various angles relative to the horizontal, a depending member carried by the frame and movable past one of the vertical supports, and a coupling device for securing the depending member to the support.

4. An awning support having spaced vertical supports, a fixed horizontal tubular member connected to the upper ends of the supports, a revolvable shaft in the tubular member, an awning cover supporting frame carried by the ends of the shaft so that the frame may be tilted to various angles relative to the horizontal, a frame-supported segment having a plurality of apertures movable past one of the vertical supports and a projection carried by the support and adapted to enter a selected aperture to secure the frame in a selected tilted position.

75

5. An awning support having spaced vertical supports, a fixed horizontal tubular member connected to the upper ends of the supports, a revolvable shaft in the tubular member, an awning cover supporting frame carried by the ends of the shaft so that the frame may be tilted to various angles relative to the horizontal, a depending member carried by the frame to move with it past one of the vertical supports and pivotally secured to the frame to swing away from the support under the influence of gravity, and a coupling device to secure the depending member to the support.

6. An awning support having spaced vertical supports, a fixed horizontal tubular member connected to the upper ends of the supports, a revolvable shaft in the tubular member, an awning cover supporting frame carried by the ends of the shaft so that the frame may be tilted to various angles relative to the horizontal, a semi-circular member having its ends secured to a frame member at points equidistant from the shaft axis for swinging movement about said frame member, whereby the semi-circular member may be moved past the vertical support and toward and away from it, and a coupling device to secure the semi-circular member to the vertical support.

7. An awning support having spaced vertical supports, a fixed horizontal tubular member connected to the upper ends of the supports, a revolvable shaft in the tubular member, an awning cover supporting frame carried by the ends of the shaft so that the frame may be tilted to various angles relative to the horizontal, the frame having end portions spaced farther apart than the supports, a pendant member carried by each end portion of the frame movable with the frame and toward and away from the adjacent support, and a coupling device for adjustably securing each pendant member to the adjacent support, the pendant members being adapted to hang free so that one may be released and the adjustment made with the other.

8. An awning support having spaced vertical supports, a fixed horizontal tubular member connected to the upper ends of the supports, a revolvable shaft in the tubular member, an awning cover supporting frame carried by the ends of the shaft so that the frame may be tilted to various angles relative to the horizontal, an arcuate member fixedly carried by the frame and movable past one of the vertical supports, a laterally extending apertured member carried by said support, the arcuate member having a plurality of apertures each adapted to be selectively brought into alignment with the apertured member, and a pin to enter the aligned apertures and secure the frame in a selected position.

9. An awning support having spaced vertical supports, a fixed horizontal tubular member connected to the upper ends of the supports, a revolvable shaft in the tubular member, an awning cover supporting frame carried by the ends of the shaft so that the frame may be tilted to various angles relative to the horizontal, a semi-circular member having its ends fixedly secured to a frame member at points equidistant from the shaft axis for swinging movement about said shaft axis, whereby the semi-circular member may be moved past the vertical support, and a coupling device to secure the semi-circular member to the vertical support.

10. An awning support having a fixed horizontal tubular member, a revolvable shaft therein,

an awning cover supporting frame secured to the ends of the shaft so that the shaft ties the frame together and the frame may be tilted to various angles relative to the horizontal, and means to secure the frame in adjusted position.

11. An awning support having a fixed horizontal tubular member, a revolvable shaft therein, an awning cover supporting frame carried by the ends of the shaft so that the frame may be tilted to various angles relative to the horizontal, and means to secure the frame in adjusted position, the frame being rectangular and fixedly secured at the mid points of its ends to the ends of the shaft.

12. An awning support having a fixed horizontal tubular member, a revolvable shaft therein, an awning cover supporting frame carried by the ends of the shaft so that the frame may be tilted to various angles relative to the horizontal, and means to secure the frame in adjusted position, the upper surface of the frame and the tubular member being in substantially a plane so that the awning cover is free of bulges.

13. An awning support having a fixed horizontal tubular member, a revolvable shaft therein, an awning cover supporting frame carried by the ends of the shaft so that the frame may be tilted to various angles relative to the horizontal, and means to secure the frame in adjusted position, the shaft axis being below the axis of the tubular member, and the frame member being above the shaft to place the upper surface of the tubular member substantially in the plane of the upper surfaces of the frame members.

14. An awning support having a fixed horizontal tubular member, a revolvable shaft therein, an awning cover supporting frame carried by the ends of the shaft so that the frame may be tilted to various angles relative to the horizontal, the tubular member having downwardly opening sockets near the ends thereof, supports entering the sockets, and means for adjustably coupling the frame and the supports.

15. An awning support having a fixed horizontal tubular member, a revolvable shaft therein, an awning cover supporting frame carried by the ends of the shaft so that the frame may be tilted to various angles relative to the horizontal, a downwardly extending member near each end of said tubular member, a vertical supporting member for each downwardly extending member, said latter mentioned members having cooperative pin and socket terminals, and means for adjustably coupling the frame and supporting members.

16. An awning support having a horizontal tubular member with downwardly opening non-circular sockets near the ends thereof, vertical supporting members having non-circular upper ends to fit the sockets and non-circular lower ends, horizontal base forming members each having an upwardly extending non-circular socket to receive the lower end of the corresponding vertical member, a revolvable shaft in the horizontal tubular member, an awning cover supporting frame carried by the ends of the shaft so that the frame may be tilted to various angles relative to the horizontal, and means for adjustably coupling the frame to the vertical members.

17. An awning frame such as claimed in claim 16, wherein the sockets and ends of the vertical members are tapering.

18. A framework for supporting an awning, comprising a horizontal fixed tubular member, a shaft therein, blocks fixedly secured to the ends

of the shaft, each block having a horizontal aperture at right angles to the axis of the tubular member, and a frame having end members passing through said apertures.

5 19. A framework for supporting an awning, comprising a horizontal fixed tubular member, a shaft therein having non-circular projecting ends, blocks removably carried by the projecting ends, transverse frame members fixedly secured 10 to the blocks, and longitudinal frame members having laterally extending portions to receive the ends of the transverse frame members.

10 20. A knock down awning support comprising two base forming members having upwardly extending coupling elements, an upper horizontal fixed tubular member having downwardly extending coupling elements near its ends, vertical 15

supporting members, the coupling elements and supporting members comprising pins and sockets so that the base forming members may detachably support the vertical members and these members detachably support the horizontal member, a revolvable shaft permanently secured in the tubular member and having its ends project beyond the same, a cover carrying frame comprising transverse members each having a non-rotatable but detachable connection with an 10 end of the shaft and horizontal members detachably connected with the ends of the transverse members, and pendant members carried by the transverse members for securing the cover carrying frame in tilted position. 15

ARTHUR JOSEPH POPE.
